(57) **CLAIM**

The ornamental design for a safety tier for exercise rack, as shown and described.

DESCRIPTION

FIG. 1 is a perspective view of a safety tier for exercise rack showing our new design;

FIG. 2 is a front view thereof.

FIG. 3 is a rear view thereof.

FIG. 4 is a left side view thereof.

FIG. 5 is a right side view thereof.

FIG. 6 is a bottom view thereof; and,

FIG. 7 is a top view thereof.

The large circular elements shown in broken lines on the side of the safety tier for exercise rack in FIGS. 1, 4 and 5 are for the purposes of showing portions of the safety tier for exercise rack which form no part of the claimed. The remaining broken lines are for the purposes of showing environmental structure which form no part of the claimed design.
